INVENTOR:

E. T. Copeland

UNITED STATES PATENT OFFICE.

EDWIN T. COPELAND, OF BROOKLYN, NEW YORK.

STEAM-BOILER.

SPECIFICATION forming part of Letters Patent No. 390,068, dated September 25, 1888.

Application filed November 3, 1887. Serial No. 254,138. (No model.)

To all whom it may concern:

Be it known that I, EDWIN T. COPELAND, a citizen of the United States, residing in Brooklyn, Kings county, and State of New York, have 5 invented certain new and useful Improvements in Steam-Boilers, of which the following is a specification, reference being had to the accompanying drawings.

My invention relates specially to the improvement of that style of water-tube boiler in which valves are provided for the purpose of disconnecting or shutting off the passage of water through any one or more of the water-tubes of which it may be composed. The 15 object of such improvements is a more reliable control of the several water-tubes and the eradication of the numerous and dangerous joints liable to leakage, and to provide for an unobstructed passage through the water-tubes 20 while in use.

My improvements consist in the combination, with the ends of the several tubes of a tubular boiler, of a manifold into which the lower ends of said tubes are fastened and 25 within which are inclosed and operated a series of valves adapted to close the immediate ends of said tubes, a tube sheet forming a portion of the steam-drum of said boiler, into which the upper ends of said tubes enter and 30 are fastened, and a series of ball-valves adapted to plug or close the associate ends of said tubes.

Referring to the drawings, Figures 1 and 2 represent a sectional elevation and horizontal cross-section of coil-boiler supplied with my 35 improvements, the manifold being applied to the lower ends of the coils and the steam and water drum, with contained check-valves, at the upper ends of the tubes. Fig. 3 is a horizontal cross-section through manifold, showing detail of valve and tube-connection. Fig. 40 4 shows the construction and application of the check-valves for the steam-drum ends of the tubes.

Similar letters of reference designate like 45 parts or portions in all the figures.

The letter A designates the steam and water drum of the coil-boiler.

B designates the water-tube portion of the boiler, coiled in this case and connected at the 50 upper end with the drum A and at the lower end with the manifold C.

C designates the manifold, containing within itself the valves D, adapted to close the ends of each of the tubes. These valves are located and operated within the manifold by means of 55 the projecting stems d. The water tubes are preferably expanded into the manifold, as shown at b' b', and into the tube-sheet of the steam-drum, as shown at b b.

E designates a series of ball check-valves 60 applied at the steam-drum ends of the water-tubes and adapted to close each its associate tube end.

F and F' are communicating pipes forming a return-connection between the drum and 65 manifold to keep up the circulation while the boiler is in operation.

G designates the uptake for smoke, and H the walls of the boiler.

To effect a control of the circulation, the 70 ball-checks are constructed to lift in the direction of the desired movement of the water and to close if the movement should by chance or accident be changed. If, for instance, while the boiler is in use a tube becomes ruptured, 75 the water blows out at the rupture, the reverse movement closes the ball-valve at the upper end, and the lower end is closed by the stop-valve D.

It is evident, of course, that the manifolds 80 C, with inclosed valves D, can be located at both ends of the tubes, it only being necessary where stop-valves are used that the stems d shall be continued through the walls of the furnace within easy reach and to be operated 85 by the fireman or engineer in charge.

I claim—

In combination with the tube ends of a water-tube boiler, the manifold C, into which the lower ends of the tubes are fastened and within 90 which are inclosed and operated a series of valves adapted to close or plug the inwardly-projecting ends of the water-tubes, the tube-sheet of the steam and water drum into which the upper ends of the tubes are fastened, and 95 a series of ball-valves adapted to close or plug the tube-sheet ends of said tubes, as and for the purposes set forth.

EDWIN T. COPELAND.
